UNITED STATES PATENT OFFICE.

BENJAMIN B. ENGLANDER, OF BROOKLYN, NEW YORK, ASSIGNOR TO ENGLANDER
SPRING BED COMPANY, OF BROOKLYN, NEW YORK.

DESIGN FOR A SPRING-MATTRESS.

49,054.

Specification for Design.

Patented May 16, 1916.

Application filed November 24, 1915. Serial No. 63,319. Term of patent 14 years.

To all whom it may concern:

Be it known that I, BENJAMIN B. ENGLANDER, a citizen of the United States, residing at Brooklyn, in the county of Kings and State of New York, have invented a new, original, and ornamental Design for Spring-Mattresses, of which the following is a specification, reference being had to the accompanying drawing, forming part thereof.

The drawing is a perspective view of a spring mattress showing my new design.

I claim as my invention:

The ornamental design for a spring mattress, substantially as shown.

Signed at Brooklyn, in the county of Kings and State of New York, this 22nd day of November, 1915.

BENJAMIN B. ENGLANDER.
